UNITED STATES PATENT OFFICE.

GEORGE FRED WINTER, OF HONOLULU, TERRITORY OF HAWAII.

HAND-PROPELLED BOAT.

Application filed October 3, 1924. Serial No. 741,473.

To all whom it may concern:

Be it known that I, GEORGE F. WINTER, a citizen of the United States, and a resident of Honolulu, Hawaii, have invented certain new and useful Improvements in Hand-Propelled Boats, of which the following is a specification.

My present invention relates generally to boats, and more particularly to a hand propelled boat propulsion of which is effected by means of levers geared with the propeller shaft having a propeller thereon at the rear of the hull, my invention contemplating a boat of small size having a closed hull upon which the operator may seat himself adjacent the levers, the hull being so constructed as to form a safe and amusing sport boat as well as one which will be safe and may be readily controlled and manipulated in use.

In the accompanying drawing which illustrates my present invention and forms a part of this specification,

Figure 1 is a side elevation showing my improved boat, partly broken away and in section.

Figure 2 is a vertical transverse section taken therethrough substantially on line 2-2 of Figure 1, and

Figure 3 is a vertical transverse section showing a slightly modified form of actuating connections.

Referring now to these figures and particularly to Figures 1 and 2 my invention proposes a boat including a closed hull 10 forming an air chamber therein, the hull being made water-tight in the first instance and being therefore non-sinkable. The hull may have a round or slightly flattened bottom 11 and its top 12 is preferably slightly convex so as to form a comfortable seat for the operator who in the manipulation and actuation of the boat straddles the hull 10, placing his feet upon the side keel members 13.

The keel members 13 are disposed at opposite sides of the hull 10 and permanently fixed thereto for the major portion of the length of the hull, the keel members being preferably of tubular form rectangular in cross section and inclined upwardly and forwardly with beveled front ends 14.

Forwardly of the center of the hull 10 a gear box 15 is fixed in depending relation therein through the top 12, this gear box being closed at its base and sides in order to

preserve the air and water-tight nature of the hull 10 and being open at its upper end. At opposite sides of the gear box bearing brackets 16 are mounted in order to support a transverse shaft 17 having thereon adjacent to its center an enlarged bevel gear 18 in mesh with a somewhat smaller bevel gear 19 upon the upper forward end of the propeller shaft 20.

The hull 10 has a tapering bow 21 and a tapering stern 22 and is provided with a rigid bearing tube 23 extending from the rear wall of the gear box 15 in downwardly and rearwardly inclined relation through the sloping stern 22. Through this tube the propeller shaft 20 is mounted, the shaft having at its rear end below the sloping stern 22 a screw propeller 24 located within a reticulate propeller guard or frame 25 at the stern of the boat which may be formed of heavy wire mesh or other suitable material capable of guarding the small light propeller 24 from harm without interfering to any material extent with its function.

The operating levers 26 of which there are two, upstand above the gear box 15 so as to be within the convenient reach of the operator seated on the hull 10, and these levers may as shown in Figures 1 and 2 pivot adjacent to their lower ends upon the transverse shaft 17 and may be provided with pawls or dogs 27 in engagement with ratchet wheels 28 secured on said shaft so that by successive manipulation of the levers 26 a practically constant rotation of the shaft 17 may be effected, power being transmitted from the latter through the gears 18 and 19 and through propeller shaft 20 to the rear propeller 24.

If it is desired, however, other forms of actuating connections may be employed as indicated in Figure 3 where the shaft 17^a is a crank shaft and the levers 26^a are pivoted at their lower ends to a supporting bracket 29 and have intermediate their ends pitmen 30 extending to the crank 31. In other respects the form of the invention shown in Figure 3 is obviously the same as that shown and described in connection with Figures 1 and 2 and according to either form it is obvious that in operation the top 12 of the hull forms a convenient seat for the operator rearwardly of the gear box 15 so that the operator's feet, straddling the hull, may conveniently rest upon the side keel members 13.

With the operator seated as above indicated it is simply necessary for him to manipulate the levers 26 in an obvious manner in order to propel the boat and as far as steering is concerned it is simply necessary for the operator to lean either to the right or the left depending upon the direction in which he wishes to turn. If it is desired to turn to the left the operator leans to the left which thus forces the left hand keel member 13 deeper into the water than the right hand keel member whereby the additional friction causes the boat to turn to the left. If a sharp turn is desired the operator not only leans to the left but may also place his left foot in the water alongside of the keel member which will thus add greatly to the friction and bring about a substantially shorter turn.

Small boats of this nature may be used with safety and great pleasure, are easy to manipulate and control, inexpensive in cost and practically without cost of upkeep under reasonable care.

25 I claim:

1. A boat including a closed hull whose top forms a seat for the operator, having

side keel members forming foot rests, and manual means including hand levers upstanding above the top of the boat for propelling the same through the water.

2. A hand propelled boat of the type described having a hull adapted to be straddled by the operator and having side keel members adapted to form foot rests, and propulsion means including hand levers projecting above the top of the hull as described.

3. A hand propelled boat including a hull adapted to be straddled by the operator and having side foot rests forming keel members.

4. A boat having a closed hull forming an air chamber therein and adapted to be straddled by the operator, and a pair of forwardly and upwardly inclined keel members at the sides thereof forming foot rests.

5. A boat having a closed hull forming an air chamber therein and a pair of keel hollow, elongated members outstanding from the sides thereof, the hull being adapted to be straddled by the operator and the keel members forming foot rests as described.

GEORGE FRED WINTER.
